PROTECTIVE SYSTEM

Norman J. McAlister, Anderson County, S. C.

Application May 2, 1934, Serial No. 723,578

3 Claims. (Cl. 89—37)

My invention relates to protective systems, and in particular to systems for protecting places of business, or other places, against robbery, hold-ups or mob violence.

5 An object of the invention is to devise a protective system of the type in which upon an attempt at robbery by an intruder, the intended victim may release a blinding powder or chemical into the atmosphere around the intruder and 10 thus effectively blind the robber and prevent his escape.

Heretofore protective systems of various kinds have been devised which depend for their operation upon the use of compressed air, electricity, and similar sources of energy. Systems employing compressed air have the disadvantage that more or less elaborate machinery is required to maintain the compressed air in a suitable storage tank, and the apparatus is subject to frequent disorder and requires constant inspection 20 and attention. In protective systems operated by electric energy, there is the disadvantage that electricity is not always available in all localities where protective systems are needed, and even 25 where electricity is available, there are frequent failures of the source of power, which renders the system not entirely reliable.

Another object of my invention is to devise a protective system which is operated entirely by 30 gravity means or by the energy stored in a suitable weight.

A further object is to devise a protective system employing guns for exploding shells loaded with a disabling dust or chemical, the system being entirely mechanical in its operation, simple of construction and adjustment, and requiring substantially no servicing.

Still another object is to devise a protective system in which a plurality of guns are located 40 at separated points of advantage and are discharged simultaneously by a common operating means located at a central point.

An additional object is to devise a novel gun construction and a gun mounting which will permit ready adjustment of the position of the gun 45 without disturbing the operating mechanism.

One arrangement of protective system according to my invention is illustrated in the accompanying drawing in which:

50 Figure 1 is an elevational view of a room in which the protective system has been installed;

Figure 2 is a sectional view of Figure 1 taken along line 2—2;

Figure 3 is a fragmentary sectional view taken 55 through the center vertical plane of one of the

gun casings, illustrating the manner in which the gun is mounted within the casing;

Figure 4 is a plan view of Figure 3;

Figure 5 is a detailed view illustrating the gun mounting; and

Figure 6 is a view partly in section illustrating the details of construction of the gun employed in the protective system.

In Figure 1 I have shown the installation of my protective system in a room having a floor represented at 1a, two side walls 1b and 1c and a ceiling 1d. Located within the room is a counter 2 across which business is to be transacted. The counter may extend all the way across the room or it may have spaces for passage around each end as shown. A casing or cabinet 3 is mounted upon the wall 1b above the left end of the counter 2, and this case contains a gun 4 for discharging shells which are loaded with a disabling charge of suitable material, and the gun is so positioned as to direct the discharge to the front of the counter and towards the center. A similar casing 3' containing a similar gun is mounted upon the side wall 1c, and the gun is directed towards the center and the front of the counter 2. A third casing 3'' is mounted above a door opening 1e and the gun in this casing is positioned to direct the charge downwardly in front of the door to prevent the escape of a would-be robber through the door without having to pass through the disabling dust or gas. Similar casings may be located at other points of advantage.

Suspended beneath the top of the counter 2 is an inverted U-bracket 5 having two spaced depending legs 5a and 5b in which is journaled a shaft 6. Secured to one end of the shaft 6 is a ratchet wheel 6a which is engaged by a pawl 6b pivotally secured near its center to the bracket 5. Fixed to the other end of the shaft 6 is an arm 6c which carries a weight 6d which is adjustable in position along the arm 6c. A suitable hand lever 6e is also secured to the shaft 6 for resetting the shaft after each operation. A tread bar 7 is located underneath the counter near the floor and extends substantially the entire length of the counter. This bar is connected to the rear end of the pawl 6b by a suitable connection 7b such as a cable, wire, or stout cord, and the bar 7 is so mounted that a depression of the bar at any place along its length will release the pawl 6b from engagement with the ratchet wheel 6a. The bar 7 may be mounted in any suitable manner, and I have shown the bar as mounted between parallel arms 7c and 7d rigidly secured to the ends of a suitable pipe or rod 7e suitably journaled in

blocks 7f and 7g located inside of the front wall of the counter 2. Suitable springs 7h may be provided to carry the weight of the bar 7 and prevent accidental tripping of the pawl 6b.

5 Three flexible cables 8, 8' and 8'' are anchored to and wound around the shaft 6, and are passed through the floor 1a and over suitable pulleys to the respective casings 3, 3' and 3'' for discharging the guns in these casings. It will be understood 10 that the arrangement is such that with the arm 6c in the position shown in Figures 1 and 2, sufficient energy is stored in the weight 6d to wind up the cables 8, 8' and 8'', when the pawl 6b is released by depressing the tread bar 7, and the 15 winding up of the cables trips the triggers of the guns in the casings 3, 3' and 3'', thereby discharging the guns. After the guns have been discharged, the operating mechanism may be reset by depressing the hand lever 6e to the position 20 shown in Figure 2.

The construction of the gun casing and the manner in which the gun is mounted within the casing is illustrated in Figures 3 to 5. The gun casing 3 is formed of a main box-like body portion 3a and a hinged cover 3b which constitutes the front wall of the casing. If desired, the front wall may be rounded in the manner shown in Figure 4, and this wall is provided with horizontal opening 3c near the bottom through which 30 the gun 4 is discharged. For the purpose of concealing the gun and camouflaging the nature of the device, a sheet of paper 3d may be arranged within the cover over the opening 3c. This paper will be destroyed each time the gun 35 is discharged and must be replaced when the gun is reloaded. For the purpose of further camouflaging the nature of the device, suitable ornamental grill-work may be provided above the opening 3c as shown. A turn-table 3e is 40 pivotally secured to the bottom of the casing by a pin 3f near the back of the casing, and this turn-table may be held at any adjusted position by means of a wing-nut 3g provided on a bolt secured to the turn-table and passing 45 through an arcuate slot 3h formed in the bottom of the casing. Mounted on the turn-table 3e is a U-bracket 3i to which the gun 4 is mounted for pivotal rotation in a vertical plane by means of a sleeve 3k. The gun is held in any position 50 of vertical adjustment by tightening the wing-nut 3m on one of the pivot bolts. A pulley 3n is mounted in front of the bracket 3i, and the operating cable 8 entering the box through a hole at the rear of the case, passes over the pulley 3n, through the bracket 3i, and is attached 55 to the trigger of the gun 4. A pair of idler pulleys 3p are arranged on opposite sides of the pivotal axis of the turn-table 3e to guide the cable 8 through the opening in back of the casing for any position of adjustment of the turn-table. The cable after passing between pulleys 3p is threaded through a spring 3s, one end of which is secured to the cable and the other end of which is suitably anchored to the bracket 65 3i under tension. The purpose of the spring 3s is to take up the slack in the cable 8 between the casing and the shaft 6 of the operating mechanism located beneath the counter 2. A limited amount of slack may be allowed in the cable 8 70 between the point of connection of the spring 3s to the cable and the trigger of the gun, and a very small amount of slack at this point will permit the gun to be adjusted either in a horizontal plane or vertical plane without disturbing the connection of the cable 8 to the trigger

of the gun. The end of the cable may be attached to the trigger by a small hook engaging the hole in the trigger directly or engaging a ring carried by the trigger, so that the cable may be readily disconnected without disturbing the gun. 80 If desired, the pulley 3n may be mounted within the bracket 3i.

The details of construction of the gun are illustrated in Figure 6. The gun is formed of a cylindrical tube 4 having an internal annular flange 4a which divides the tube into a barrel section to the right, into which the shells are loaded through the muzzle end of the tube, and a plunger section to the left. The shells are retained in the barrel by means of a cap 4b arranged over the muzzle end of the barrel and secured to the barrel by means of a pin and bayonet-slot connection. This cap must be removed to reload the gun. The rear section of the tube 4 is closed at the left end, and a plunger 4c, carrying the firing pin, is arranged to operate in this section and is provided with a stem 4d extending through the rear end of the case. A knob 4e is secured to the end of the stem 4d by means of which the gun is cocked. A compression spring 4f is arranged within the tube surrounding the stem 4d and presses against the plunger 4c. A trigger 4g is pivotally secured to the tube and serves to hold the plunger 4c in cocked position. A suitable spring, such as 4h, 105 is provided to bias the trigger to the latching position. If desired, an annular washer or ring 4i of resilient material, such as rubber, may be inserted between the plunger 4c and the annular shoulder 4a to hold the firing pin out of 110 contact with the shell while the gun is being reloaded. It will be understood that when the trigger is released, the force of the plunger against the resilient washer compresses the washer and permits the pin to strike the firing 115 cap of the shell.

The shells employed in the guns of my protective system are of the same general construction as shells commonly used in shot guns. It will be understood that the shells are provided with the 120 usual firing cap and a quantity of gun powder loaded in the section next to the cap. A quantity of disabling powder or dust is loaded in the front end of the shell, and the shell is then closed by a suitable packing. The material to be loaded 125 in the shells should be one which effectively blinds or stifles a person for twenty to thirty minutes in order to give an opportunity to capture the intruder. Several materials will be found satisfactory for this purpose. For example, I may 130 use a chemical such as veratrine or veratrine hydrochloride or materials such as Cayenne pepper, snuff, lime dust, or mixtures of the above materials.

Since the entire operating energy for firing the 135 guns is supplied by the weight, and since very little force is required to trip the pawl, my system insures positive operation of the guns upon a very slight depression of the tread bar. In other words, my system involves a force multiplying 140 relay in which a small force sets into operation a larger and positively acting force to fire the guns.

While I have illustrated and described one installation of my protective system in which the operating mechanism for firing the guns is located 145 beneath a counter, and a tread bar is provided for tripping the operating mechanism, it will be understood that the operating mechanism might be placed in other locations and tripped by means other than a tread bar. I prefer to conceal the 150

operating cables by placing them beneath the floor and between the walls of the building as illustrated, but this is not essential to the invention.

5 If desired, an audible signal device may be arranged within the room, or outside of the room, and a connection made between one of the operating cables to set the signal into operation when the guns are discharged. This signal 10 may be located in one of the gun casings, or it may be arranged in a separate housing located outside of the building in order to attract the attention of persons on the outside. The audible signal may be of any desired construction, but 15 I prefer one which is operated by a weight-motor such as is commonly employed in clocks.

While I have shown a particular gun construction especially designed for operation in my protective system, it will be understood that 20 other forms of gun may be used. For example, a breech loading gun may be employed, and the gun may be removably mounted upon the turn-table in order to facilitate loading. Also, instead of using specially constructed shells, it is 25 possible to use ordinary shot gun shells by removing the shot from the end of the shell, and replacing the shot with a suitable disabling powder. In case the shell does not hold a sufficient amount of powder, the proper quantity 30 may be loaded in the muzzle of the gun and retained in position by a suitable packing.

While I have illustrated and described one embodiment of my protective system, as required by the patent statutes, it will be obvious 35 to those skilled in the art that the system may be modified in various ways without departing from the spirit of the invention.

What I claim is:

1. In a gun-mount, the combination of a base

member, a turn-table pivoted to said base member, a gun mounted upon said turn-table, a firing cable secured to the trigger of said gun, and a tension spring secured at one end to said turn-table and at the other end to said cable to take up the slack in said cable between said turn-table and the cable operating means.

2. In a gun-mount, the combination of a base member, a turn-table pivoted to said base member, a gun mounted upon said turn-table, a firing cable secured to the trigger of said gun, a tension spring secured at one end to said turn-table and at the other end to said cable to take up the slack in said cable between said turn-table and the cable operating means, and a pair of idle pulleys arranged on opposite sides of the pivotal axis of said turn-table between which said cable is located, whereby said turn-table may be moved about its axis without causing said cable to trip said trigger.

3. In a gun-mount, the combination of a base member, a turn-table pivoted to said base member, means for locking said turn-table to said base and permitting adjustment of said turn-table about its pivotal axis, a gun mounted upon said turn-table for pivotal movement about an axis at right angles to the axis of said turn-table, a firing cable secured to the trigger of said gun, a tension spring secured at one end to said turn-table and at the other end to said cable to take up the slack in said cable between said turn-table and the cable operating means, and a pair of idle pulleys arranged on opposite sides of the pivotal axis of said turn-table between which said cable is located, whereby said turn-table may be moved about its axis without causing said cable to trip said trigger.
